EXCAVATING MACHINE

Samuel Lippincott Griswold Knox,
Englewood, N. J.

Application July 3, 1933, Serial No. 678,969

22 Claims. (Cl. 214—135)

This invention relates to improvements in excavating machines of the power shovel, dredge, and like types.

The usual construction of the digging mechanism of power shovels, dredges and the like, consists of an inclined boom, the lower end of which rests on the main structure of the machine, the upper end being supported by guys which are generally anchored to a mast, which in 10 turn is anchored to the rear end or part of the structure carrying the hoisting machinery. About the middle of the boom a saddle block is hinged, through which passes the dipper handle under control of the shipper shaft about which 15 the saddle block is pivoted. The actual digging element, the dipper, is attached to the lower end of the dipper handle. There is also attached to the dipper a rope, or ropes, which pass over a sheave or sheaves at the outer end of the boom 20 and thence to the hoisting machinery. The boom is usually inclined about 45° to the horizontal. Means are provided for causing the dipper handle to move in and out through the saddle block.

While the aforementioned structure has persisted through many years, it has decided drawbacks. As ordinarily constructed, in order to get a good dumping height for the dipper, there results at lower dipper positions a relatively poor digging force from a given rope pull. If, on the other hand, the boom is so designed, or mounted, that the pull of the digging rope has a good component in the direction of digging, either the undesirable limitation to the dumping height or excessive length of boom and dipper handle, or 30 both of these objectionable features, result. Further, the conventional method of supporting the boom with guys attached to its upper end, about twice as far from its base as the point where the shipper shaft is located, has serious drawbacks 35 in that considerable strains are transmitted to the boom at a place approximately midway between its points of support, thereby producing severe bending stresses. The boom and dipper handle are also subject to severe stresses as a 40 result of the swinging action. Not only are considerable stresses set up by the acceleration and retardation of the boom, dipper, and dipper handle, but operators are apt to start swinging while the dipper is still digging, and to drop the dipper 45 into the material being dug before the rotation has been stopped. The resultant torsional stresses in the boom and bending in the dipper handle are very difficult to take care of in the usual type of construction. This is because when 50 the boom is continuous from shovel platform to

the point where the sheave over which the hoisting rope leads to the dipper is supported, either the boom or the dipper handle must be divided, as they cross each other at the shipper shaft. If the boom is divided, its torsional strength, for 5 a given weight of material, is reduced. If the dipper handle is divided, its strength as a beam is correspondingly reduced.

Among the objects of the present invention which is designed to overcome the aforementioned objections in conventional power shovel or like constructions may be noted the provision of an improved boom construction; the provision of digging means in which the strain in and therefore the weight of the boom and dipper handle for a given effective digging force are reduced 10 while at the same time the maximum effective dumping height of the dipper may be maintained or increased; the provision of digging means including a boom and dipper handle in 15 which the material constituting said boom and dipper handle is used more efficiently for carrying the strains applied thereto than in the conventional constructions; the provision of digging means for increasing the effective digging pull 20 and dumping height of the digging element.

Other objects will be in part obvious from the annexed drawing and in part indicated from the following analysis of this invention, in which reference is made to the accompanying drawings 30 illustrating an embodiment of my idea.

In the drawings—

Fig. 1 is an elevation illustrating my improved digging construction, with the dipper handle in its lowermost position illustrated in full lines, and 35 its raised position illustrated in dotted lines;

Fig. 2 is a detail in side elevation of the shipper shaft assembly, with the dipper handle in "down" position;

Fig. 3 is a sectional detail through the shipper 40 shaft assembly, with the dipper handle in its "up" or raised position; and

Figs. 4—7 represent in elevation modified constructions in accordance with my invention.

Referring to the drawings, reference numeral 45 10 indicates the main supporting structure which may be a platform, dredge body, or the like. Numeral 11 indicates a boom inclined about 40° to the horizontal, although this angle may vary, whose lower end is supported on structure 10 and 50 whose upper end is supported by a strut 12 from a mast or A-frame 13 or other structure of the shovel support proper. According to my improved construction, boom 11 ends short of the shipper shaft 15, which latter is journaled in spaced ears 55

- 16 formed on a head 17 secured fast to the upper end of the boom 11. 18 is a saddle block hinged to turn about shipper shaft 15, with the dipper handle 20 passing through said saddle block. It will be obvious that the dipper handle 20 moves outside the end of boom 11 instead of straddling it, or passing through it, as in the usual type of shovel and dredge construction, and neither the boom 11 nor the dipper handle 20 need be split.
- 10 The dipper handle 20 may have provided along one face a rack 21 cooperating with a pinion 22 fast on shipper shaft 15, the shaft and pinion being turned positively and/or braked by suitable instrumentalities (not shown) cooperating with gear 23 (Fig. 3) keyed or otherwise secured to shipper shaft 15 as is conventional. Dipper handle 20 is provided at its lower end with a digging element proper, hereinafter referred to as dipper 24.
- 20 In my improved construction, the digging rope 30 which is secured to dipper 24, instead of passing over a sheave at the end of the boom as in the known constructions, passes over sheave 31 at the end of parallel strut construction 32, said strut forming an arm of a frame unit 32, 33, 34 to be more fully described hereinafter. Digging ropes 30 pass over sheave 31 as aforesaid, thence over sheaves 35 rotatable on shipper shaft 15, and thence to a hoisting drum 36 arranged on the platform or main structure 10, the drum being driven by suitable means such as gearing 37, 38 from suitable power means indicated generally at 40.
- Referring to the frame unit 32, 33, 34 of Figs. 1-3 construction, said frame consists of strut 32 as aforesaid together with a strut construction, 33, said struts 32, 33 being arranged with their ends attached to angular plate 42, the frame being rotatable about the axis of the shipper shaft 15. The remaining side 34 of the frame may be constituted by guys or struts and may even consist of an extension of the raising rope 43 in which case the latter would be attached to the outer ends of struts 32, 33 and might bend over a curved segment attached to strut 33 or its equivalent, as will be hereinafter described in relation to Fig. 4. The frame 32, 33, 34 is operated by rope 43 which passes over a sheave 44 supported at the upper end of mast 13, the rope 43 thereupon passing to hoisting drum 36 or to another drum suitably driven from power means 40.
- In the Fig. 1 construction, connection of frame 32, 33, 34 with structure 10 may be fixed or variable. When variable, frame 32, 33, 34 rises and falls in cyclical relation to the movement of dipper 24, as rope 43 is reeled or paid out. When the dipper is in its down position for digging, the frame 32, 33, 34 is also in its down position as is illustrated in full line position, Fig. 1, such arrangement giving a greatly improved digging component of the pull in the hoisting rope. Conversely, as the dipper rises to its dumping position, the frame 32, 33, 34 will also rise to such an angle that the said dumping position of the dipper may be higher than is possible with the conventional construction when the latter is so arranged that a comparable digging component of the pull in the digging rope is obtainable at the lower dipper positions, all as illustrated in the dotted line position of dipper and frame, Fig. 1.
- 70 With the aforesaid arrangement, the effective digging effort for a given pull in the digging rope 30 may easily be doubled or tripled while the effective dumping height is maintained or increased for a given total distance from base of boom 11 to sheave 31. At the same time the weight of the

structure replacing the conventional boom is reduced to less than half that of the continuous boom type for a given pull in hoisting rope 30.

Frame 32, 33, 34 whose connection to boom 11 and mast 13 has been previously described as variable may also remain fixed, that is to say, under some conditions, and for certain types of work, it might be advisable to maintain the frame 32, 33, 34 fixed in a particular position. This may be effected by adjusting the frame raising rope 43 to 10 raise and maintain the frame in such position, in which event strut 32 acts as an extension of boom 11, while providing the advantages of a light, strong structure for extending the point of boom sheave 31 out to its desired position, and at the 15 same time removing all bending stresses from the boom and making that part of the boom from the shipper shaft 15 to boom sheave 31 into a strut construction.

Frame 32, 33, 34 may further be moved at any 20 angular speed from zero (its fixed position aforesaid) up to the angular speed of the dipper 24 itself, within the limits of the present invention. While the drawing illustrates ropes 30 and 43 running on to drums of the same diameter, this 25 proportioning of drums is not essential and in many cases such proportioning would not be followed, or, if followed, the drums could be driven by different gear trains so as to give different drum R. P. M.'s. Where the frame 32, 33, 34 30 moves at zero angular speed with respect to the angular speed of dipper 24, the frame would remain fixed as aforesaid, in which event the dipper action would come entirely from action of rope 30. Where the angular speed of the frame 35 32, 33, 34 equals the angular speed of the dipper, rope 30 becomes a mere tie from point of dipper 24 to the end of strut 32 with the distance between dipper and outer end of strut 33 being fixed, and the entire hoisting motion is effected by rocking 40 frame 32, 33, 34 up and down by means of rope 43. Any intermediate angular speed of the frame 32, 33, 34 from zero to that of the dipper 24 may be obtained by suitably proportioning the hoisting drums 36 and/or the gearing thereof, and/or 45 by other suitable means, causing the strut 32 to rise and fall in the desired relation to the movement of dipper 24.

It would of course also be possible to vary the length of the boom guy 12 during the digging 50 cycle, thus causing the angle between boom 11 and platform 10 to vary. In this way, it is possible under certain conditions to do away with rack and pinion or corresponding means for moving the dipper handle through the saddle block. 55

Referring to Fig. 4, there is described a modified construction suggested in the foregoing, in which frame raising rope 43 bends over a curved segment 45 secured to strut 33 and braced by suitable side arms 46 attached to the angle plates 42 as 60 shown in Figs. 2 and 3. The segment accordingly moves with the frame parts 32, 33 upon manipulation of rope 43. By such an arrangement an effective arm for the pull of rope 43 can be maintained throughout a wide range of angular movements of the frame 32, 33, 34.

In Fig. 5, I have illustrated a further modified construction in which the movable frame construction 32, 33, 34 is substituted by a swingable strut 32a similar to strut 32 aforesaid. Strut 70 raising rope 43a secured at end of strut 32a passes over sheave 47 supported by fixed struts 48 extending from mast 13. Strut 32a is movable in the same manner as frame 32, 33, 34 of the Fig. 1 construction.

In Fig. 6, I have illustrated a further modified construction following generally the Fig. 5 modification, according to which mast 13a is extended and raked forwardly to carry sheave 47 over which 5 strut raising rope 43a passes, with the sheave carrying struts 48 of the Fig. 5 construction omitted. While the angular movement of sheave carrying strut 32a is perhaps somewhat more limited than in the construction shown in Figs. 1 and 5, for example, such modified constructions permit a far better digging angle than the conventional construction.

In Fig. 7, I have illustrated a modified construction designed for particular cases where simplicity of construction and mechanism may be more important than the combination of all of the advantages hereinafter described, in which the oscillating frame 32, 33, 34 as described in relation to Fig. 1 is not considered necessary. In 10 this modified construction, a light, strong structure comprising parallel struts 50 carries the point of boom sheave 51. Struts 50 are supported at their lower ends by pins or trunnions at or near the axis of the shipper shafts 15. The brace 25 54 supports the upper end of boom 11 from the mast 55 which in turn is supported from the platform or equivalent structure 56. In this modified construction the entire digging action is effected through manipulation of dipper rope 58 passing over sheave 51 and thence to hoisting drum 60 mounted on platform 56. By the aforesaid arrangement, digging power is applied to the dipper in the conventional manner, but practically all bending stresses are removed from the boom by 30 using a simple strut 50 from shipper shaft 15 to the boom sheave 51, so supported at its lower end that this strut, the brace 54, and the guys 61 are so connected that there are no significant bending or torsional stresses in them in addition to the 35 direct compression or tension stresses due to the digging and thrusting actions.

Without further analysis, the foregoing will so fully reveal the gist of this invention that others can by applying current knowledge readily adapt 40 it for various applications without omitting certain features that from the standpoint of the prior art, fairly constitute essential characteristics of the generic or specific aspects of this invention, and therefore such adaptations should 45 and are intended to be comprehended within the meaning and range of equivalency of the following claims.

I claim:

1. In apparatus of the character described, in 50 combination, a supporting structure, a boom supported in an inclined position upon said structure, a shipper shaft operatively related to the boom and mounted adjacent the extreme upper end thereof, a dipper handle under the control of 55 said shipper shaft and carrying at its lower end a dipper, a hoisting rope operatively attached to said dipper and extending to hoisting machinery, a sheave over which said hoisting rope passes, and a sheave mounting flexibly connected to the 60 extreme upper end of the boom and operative to position said sheave beyond said extreme upper end of the boom.

2. In apparatus of the character described, in 65 combination, a supporting structure, a boom supported in an inclined position upon said structure, a shipper shaft operatively related to the boom and mounted at the upper end thereof, a dipper handle under the control of said shipper 70 shaft and carrying at its lower end a dipper, a hoisting rope operatively attached to said dipper and extending to hoisting machinery, a frame unit associated with said boom and including a strut carrying a sheave disposed beyond the upper end of the boom, said hoisting rope passing over said sheave, and means for moving said 75

and extending to hoisting machinery, a sheave carrying said rope, and means supporting said sheave and movable relatively to the boom during the digging cycle at angular speeds from zero up to the angular speed of the dipper for increasing the effective digging pull and dumping height of the dipper. 5

3. In apparatus of the character described, in combination, a supporting structure, a boom supported in an inclined position upon said structure, a shipper shaft operatively related to the boom and mounted adjacent the extreme upper end thereof, a dipper handle under the control of said shipper shaft and carrying at its lower end a dipper, a hoisting rope operatively attached to 10 said dipper and extending to hoisting machinery, and a strut construction operatively connected to and extending beyond said boom and carrying a sheave over which the hoisting rope passes. 15

4. In apparatus of the character described, in combination, a supporting structure, a boom supported in an inclined position upon said structure, a shipper shaft operatively related to the boom and mounted at the upper end thereof, a dipper handle under the control of said shipper 20 shaft and carrying at its lower end a dipper, a hoisting rope operatively attached to said dipper and extending to hoisting machinery, a strut construction extending beyond said boom and carrying a sheave over which the hoisting rope 25 passes, and means for imparting movement to said construction relatively to the boom during the digging cycle and in desired cyclical relation to the movement of the dipper. 30

5. In apparatus of the character described, in combination, a supporting structure, a boom supported in an inclined position upon said structure, a shipper shaft operatively related to the boom and mounted at the upper end thereof, a dipper handle under the control of said shipper 35 shaft and carrying at its lower end a dipper, a hoisting rope operatively attached to said dipper and extending to hoisting machinery, a strut construction flexibly connected to and extending beyond said boom and carrying a sheave over 40 which the hoisting rope passes, and means for actuating said strut construction relatively to the boom during the digging cycle and at a desired angular speed from zero up. 45

6. In apparatus of the character described, in combination, a supporting structure, a boom supported in an inclined position upon said structure, a shipper shaft operatively related to the boom and mounted adjacent the extreme upper end thereof, a dipper handle under the control of said 55 shipper shaft and carrying at its lower end a dipper, a hoisting rope operatively attached to said dipper and extending to hoisting machinery, and a frame unit flexibly connected to said boom and including a strut carrying a sheave disposed 60 beyond the upper end of the boom, said hoisting rope passing over said sheave. 65

7. In apparatus of the character described, in combination, a supporting structure, a boom supported in an inclined position upon said structure, a shipper shaft operatively related to the boom and mounted at the upper end thereof, a dipper handle under the control of said shipper 70 shaft and carrying at its lower end a dipper, a hoisting rope operatively attached to said dipper and extending to hoisting machinery, a frame unit associated with said boom and including a strut carrying a sheave disposed beyond the upper end of the boom, said hoisting rope passing over said sheave, and means for moving said 75

- frame element relatively to the boom during the digging cycle and at a desired angular speed from zero up.
8. In apparatus of the character described, in combination, a supporting structure, a boom supported in an inclined position upon said structure, a shipper shaft operatively related to the boom and mounted at the upper end thereof, a dipper handle under the control of said shipper shaft and carrying at its lower end a dipper, a hoisting rope operatively attached to said dipper and extending to hoisting machinery, a frame unit associated with said boom and including a strut carrying a sheave disposed beyond the upper end of the boom, said hoisting rope passing over said sheave, and means for moving said frame unit relatively to the boom during the digging cycle and in desired cyclical relation to the movement of the dipper.
9. In apparatus of the character described, in combination, a supporting structure, a boom supported in an inclined position upon said structure, a shipper shaft operatively related to the boom and mounted at the upper end thereof, a dipper handle under the control of said shipper shaft and carrying at its lower end a dipper, a hoisting rope operatively attached to said dipper and extending to hoisting machinery, a frame unit mounted for angular movement on an axis at or near the axis of said shipper shaft, said frame unit including a strut and a sheave carried at the outer end thereof over which the hoisting rope passes, and means for imparting movement to said frame unit.
10. In apparatus of the character described, in combination, a supporting structure, a boom supported in an inclined position upon said structure, a shipper shaft operatively related to the boom and mounted at the upper end thereof, a dipper handle under the control of said shipper shaft and carrying at its lower end a dipper, a hoisting rope operatively attached to said dipper and extending to hoisting machinery, a frame unit flexibly connected to the boom for angular movement on an axis at or near said shipper shaft, said frame unit including a strut and a sheave carried at the outer end thereof, over which the hoisting rope passes, and means for imparting movement to said frame unit at a desired speed from zero up.
11. In apparatus of the character described, in combination, a supporting structure, a boom supported in an inclined position upon said structure, a shipper shaft operatively related to the boom and mounted at the upper end thereof, a dipper handle under the control of said shipper shaft and carrying at its lower end a dipper, a hoisting rope operatively attached to said dipper and extending to hoisting machinery, a frame including angularly related struts movable as a unit on an axis at or near the axis of said shipper shaft, one of said struts carrying near its outer end a sheave over which said hoisting rope passes, a frame moving rope operatively connected to the other strut and extending to said hoisting machinery, and adapted to actuate the frame about its axis.
12. In apparatus of the character described, in combination, a supporting structure, a boom supported in an inclined position upon said structure, a shipper shaft operatively related to the boom and mounted at the upper end thereof, a dipper handle under the control of said shipper shaft and carrying at its lower end a dipper, a hoisting rope operatively attached to said dipper

and extending to hoisting machinery, a frame flexibly connected to the boom and including angularly related struts movable as a unit on an axis at or near the axis of said shipper shaft, one of said struts carrying near its outer end a sheave over which said hoisting rope passes, a frame moving rope operatively connected to the other strut and extending to said hoisting machinery and adapted to actuate the frame about its axis at a desired speed from zero up.

13. In apparatus of the character described, in combination, a supporting structure, a boom supported in an inclined position upon said structure, a shipper shaft operatively related to the boom and mounted at the upper end thereof, a dipper handle under the control of said shipper shaft and carrying at its lower end a dipper, a hoisting rope operatively attached to said dipper and extending to hoisting machinery, a frame including a strut, a sheave carried at the end thereof over which the hoisting rope passes, and a segment, the said frame unit being movable on an axis at or near the axis of said shipper shaft, and a frame actuating rope attached to said strut and passing over the segment and extending to said hoisting machinery.

14. In apparatus of the character described, in combination, a supporting structure, a mast thereon a boom supported in an inclined position upon said structure and from said mast, a shipper shaft operatively related to the boom and mounted at the upper end thereof, a dipper handle under the control of said shipper shaft and carrying at its lower end a dipper, a hoisting rope operatively attached to said dipper and extending to hoisting machinery, a strut mounted for movement on an axis at or near the axis of said shipper shaft, a sheave carried at the outer end of said strut over which said hoisting rope passes, a strut actuating rope attached to said strut, and a sheave supported from said mast, said last-named rope passing over said last-named sheave and thence to said hoisting machinery.

15. In apparatus of the character described, in combination, a supporting structure, a boom supported in an inclined position upon said structure, a shipper shaft operatively related to the boom and mounted at the upper end thereof, a dipper handle under the control of said shipper shaft and carrying at its lower end a dipper, a hoisting rope operatively attached to said dipper and extending to hoisting machinery, a strut mounted for movement on an axis at or near the axis of said shipper shaft, a sheave carried at the outer end of said strut over which said hoisting rope passes, a strut actuating rope attached to said strut, a fixed strut supported on said supporting structure, and a sheave carried by said strut, said last-named rope passing over said last-named sheave and thence to the hoisting machinery.

16. In apparatus of the character described, in combination, a supporting structure, a mast supported on said structure, a boom supported in inclined position upon said structure and from said mast, a shipper shaft operatively related to the boom and mounted at the upper end thereof, a dipper handle under the control of said shipper shaft and carrying at its lower end a dipper, a hoisting rope operatively attached to said dipper, a strut mounted for movement about an axis at or near the axis of said shipper shaft, a sheave carried at the outer end of said strut over which said hoisting rope passes, a strut actuating rope attached to said strut, a sheave carried by said

mast, said strut actuating rope passing over said last-named sheave and thence to said hoisting machinery.

17. In apparatus of the character described, in combination, a supporting structure, a mast supported thereon, a boom supported in inclined position upon said structure and tied to said mast, a shipper shaft operatively related to the boom and mounted at the upper end thereof, a dipper handle under the control of said shipper shaft and carrying at its lower end a dipper, a strut construction supported at one end at or near the axis of said shipper shaft, guys extending between the other end of said strut construction and said mast, a sheave carried at said upper end of the strut construction, and a hoisting rope operatively attached to said dipper and passing over said sheave and thence to suit-

and passing over said sheave and thence to said
able hoisting mechanism.

20 18. In apparatus of the character described, in
combination, a supporting structure, a boom sup-
ported in an inclined position upon said struc-
ture, a shipper shaft operatively related to the
boom and mounted adjacent the extreme upper
25 end thereof, a dipper handle under the control of
said shipper shaft and carrying at its lower end
a dipper, a hoisting rope operatively attached to
said dipper and extending to hoisting machinery,
a strut construction, flexibly connected to said
30 boom adjacent the shipper shaft and extending
beyond said boom and carrying a sheave over
which the hoisting rope passes, suspension means
for said boom, and suspension means for said
strut.

Strut.

35 19. In apparatus of the character described, in combination, a supporting structure, a boom supported in an inclined position upon said structure, a shipper shaft operatively related to the boom and mounted adjacent the extreme upper end thereof, a dipper handle under the control of said shipper shaft and carrying at its lower end a dipper, a hoisting rope operatively attached to said dipper and extending to hoisting machinery, a light strut construction operatively connected to and extending beyond said boom and carrying a sheave over which the hoisting rope passes, suspension means for said boom extending from said supporting structure to said boom, and suspension means for said strut extending from said supporting structure to said strut.

40

45

50

30 20. In apparatus of the character described, in combination, a supporting structure, a boom supported in an inclined position upon said struc-

ture, a shipper shaft operatively related to the boom and mounted adjacent the extreme upper end thereof, a dipper handle under the control of said shipper shaft and carrying at its lower end a dipper, a hoisting rope operatively attached to said dipper and extending to hoisting machinery, a light strut construction connected to said boom adjacent the shipper shaft and extending beyond said boom and carrying a sheave over which the hoisting rope passes, suspension means for said boom extending from said supporting structure to said boom, and suspension means for said strut extending from said supporting structure to said strut. 5 10

21. In an excavating machine of the dipper 15 type, the combination of: a base; an A-frame mounted on said base; a hoisting winch, supported by said base; an inclined boom, with its bottom end supported on said base; a shipper shaft, mounted adjacent the extreme upper end of the 20 boom; a dipper handle, under the control of said shipper shaft; a digging dipper, mounted on the lower end of the dipper handle; a light strut construction, with its lower end connected to said boom adjacent the shipper shaft, and extending 25 beyond the boom; a sheave, carried by the strut, adjacent its outer end; a hoisting rope operatively related to said dipper and handle, and extending over the sheave to the hoisting winch; means suspending the boom from the A-frame; and 30 means independently suspending the strut from the A-frame.

22. In an excavating machine of the dipper type, the combination of: a base; an A-frame mounted on said base; a hoisting winch, supported by said base; an inclined boom, with its bottom end supported on said base; a shipper shaft, mounted adjacent the extreme upper end of the boom; a dipper handle, under the control of said shipper shaft; a digging dipper, mounted on the lower end of the dipper handle; a light strut construction, with its lower end connected to said boom adjacent the shipper shaft, and extending beyond the boom; a sheave, carried by the strut, adjacent its outer end; a hoisting rope operatively related to said dipper and handle, and extending over the sheave to the hoisting winch; means suspending the boom from the A-frame; and means suspending the strut from the A-frame so as to cause no buckling tendency of the joint which connects the strut to the boom. 35 40 45 50

SAMUEL LIPPINCOTT GRISWOLD KNOX.
